UNITED STATES PATENT OFFICE.

CHARLES L. FROST, OF GRAND RAPIDS, MICHIGAN.

DESIGN FOR A DOOR-CATCH.

SPECIFICATION forming part of Design No. 28,488, dated April 19, 1898.

Application filed October 1, 1897. Serial No. 653,760. Term of patent 14 years.

To all whom it may concern:

Be it known that I, CHARLES L. FROST, a citizen of the United States, residing at Grand Rapids, in the county of Kent and State of Michigan, have invented and produced a new and original Design for Furniture Door-Catches, of which the following is a specification, reference being had to the accompanying drawings, forming a part thereof.

5 In the accompanying drawings, Figure 1 is a perspective of the catch, and Fig. 2 is a cross-section of the same on line xx of Fig. 1.

The main feature of my design consists in the disk A, having a prominent incline a on 15 one side, prominent high corners forming

protecting-walls a' each side of the incline, and a deep receiving-notch a^2 central of the disk.

Having thus fully described my invention, what I claim as new, and desire to secure by 20 Letters Patent, is—

The design for a door-catch herein shown and described.

Signed at Grand Rapids, Michigan, September 29, 1897.

CHARLES L. FROST.

In presence of—

ITHIEL J. CILLEY,
ANDREW ALLGIER.
